(57) **CLAIM**

The ornamental design for a two-piece relief valve component, as shown and described.

DESCRIPTION

FIG. 1 is a side perspective view of a two-piece relief valve component showing our new design;

FIG. 2 is a bottom perspective view thereof;

FIG. 3 is a left side view thereof;

FIG. 4 is a right side view thereof;

FIG. 5 is a top plan view thereof;

FIG. 6 is a bottom plan view thereof; and,

FIG. 7 is an exploded side perspective view thereof.

The broken lines shown in the drawings are for purposes of illustrating portions of the two-piece relief valve component which form no part of the claimed design.
